CLAIM

The ornamental design for intraocular lens injector holder, as shown and described.

DESCRIPTION

FIG. 1 is a perspective view showing the top, front and left side of the intraocular lens injector holder.

FIG. 2 is a plan view showing the top of the intraocular lens injector holder of the present invention;

FIG. 3 is an elevation view showing the front of the intraocular lens injector holder of the present invention.

FIG. 4 is an elevation view showing the left side of the intraocular lens injector holder of the present invention;

FIG. 5 is an elevation view showing the right side of the intraocular lens injector holder of the present invention.

FIG. 6 is an elevation view showing the rear of the intraocular lens injector holder of the present invention; and,

FIG. 7 is a plan view showing the bottom of the intraocular lens injector holder of the present invention.

The broken line showing of environment in FIG. 1 is for illustrative purposes only and forms no part of the claimed design.
